T. D. FINIZIO

ATTACHING PLUG

Filed Aug. 11, 1921

Inventor

THOMAS D. FINIZIO

BY *Conrad M. Dietrich*
his Attorney

UNITED STATES PATENT OFFICE.

THOMAS D. FINIZIO, OF YORKTOWN HEIGHTS, NEW YORK.

ATTACHING PLUG.

Application filed August 11, 1921. Serial No. 491,400.

My invention relates to improvements in electrical attachment plugs, and the same has for its object more particularly to provide a plug in which the contact terminals may engage throughout their entire length with the element adapted to be inserted into the same.

Further, said invention has for its object to provide a plug in which the contact terminals are each composed of a pair of jaws which are adapted to contact throughout their entire length with the contact pin or blade adapted to be inserted between the same.

15 Further, said invention has for its object to provide a plug in which each contact terminal comprises a rigid member, and a member bodily movable with respect thereto when a contact element is introduced therebetween.

20 Further, said invention has for its object to provide a plug in which each contact member comprises a rigid jaw and a movable jaw which is engaged intermediate its ends by said fixed jaw and has its opposite ends 25 free to move with respect to said fixed jaw.

Further, said invention has for its object to provide a plug in which each contact member comprises a rigid jaw, and a bodily yielding jaw which are so arranged that the 30 insertion of a cooperating contact element will, at first, be resisted by a comparatively small degree of pressure, and thereafter by a gradually increasing pressure until the same is fully in position between said jaws.

35 Further, said invention has for its object to provide a plug in which the several parts of the contact terminal or member may be readily assembled and held in place by a single screw or the like which also serves to 40 secure one end of a conductor thereto.

Further, said invention has for its object to provide a plug in which the contact terminals or members are adapted, without change or alteration, to receive and hold a 45 cooperating contact element which may be either cylindrical or flat, or substantially cylindrical or flat in form.

Other objects will in part be obvious and in part be pointed out hereinafter.

50 To the attainment of the aforesaid objects and ends, my invention consists in the novel details of construction, and in the combination, connection and arrangement of parts hereinafter more fully described and then pointed out in the claims.

In the accompanying drawings wherein like numerals of reference indicate like parts—

Figure 1 is a face view, partly broken away, showing one form of attachment plug constructed according to, and embodying my said invention, the said view showing one contact terminal or member in plan or face view;

Fig. 2 is a side elevation of one contact terminal or member, showing the positions of the several parts when a removable contact member of cylindrical form is being inserted into the same.

Fig. 3 is a similar view showing the removable contact member fully in position and engaged by the jaws of the contact terminal or member of the plug;

Fig. 4 is a cross-section on the line 4—4 of Fig. 3; and

Fig. 5 is a similar view showing the jaws of said contact terminal embracing a flat removable contact element.

In said drawings 10 designates a casing, made of suitable insulating material, and 80 preferably comprising a base 11 and a cover 12 corresponding in outline thereto. The base 11 and cover 12 are provided in their opposing faces with registering recesses 13 corresponding in outline with the general 85 contour of the contact terminals or members 14 adapted to be maintained in separated relation therein when said parts 11 and 12 are secured in assembled position by bolts 15 and nuts 16.

Each contact terminal or member 14 comprises a longitudinally grooved plate 17 having a flaring forward end 18 and a flat rear substantially rectangular end 19 provided along its sides with upwardly projecting flanges 20, and with upwardly extending ears 21.

The longitudinally grooved plate 17 is provided at its opposite longitudinal edges with flat, laterally extending flanges 22.

23 denotes a pair of spaced projections arranged adjacent to the forward end of the plate 17 and extending upwardly from the outer edges of the flanges 22.

24 denotes a shorter longitudinally grooved plate having a flaring forward end 25 corresponding to the flaring forward end 18 of the plate 17, and having its rear end slightly rounded at 25a. The said grooved plate 24 is also provided along its opposite longitu-

dinal edges with flat, laterally extending flanges 26 corresponding to the flanges 22 of the lower grooved plate 17, and at its opposite edges midway between its ends said plate 24 is provided with lateral projections 27 adapted to be loosely received intermediate each pair of spaced projections 23 in order to maintain said plate 24 duly positioned against longitudinal movement with respect to the plate 17.

28 denotes a flat spring having its rear end disposed intermediate the flanges 20 and the ears 21 on the rear end 19 of the plate 17, and secured in position thereon by the screw 29 and washer 30 which serve to hold one end of an electric conductor 31 secured to said contact terminal 14. The forward portion of the flat spring 28 extends upwardly and forwardly and has its free end in contact with the upper side of the movable plate 24 at about a point coinciding with a line drawn at right angles to the longitudinal axis of said plate 24 and extending centrally through the projections 27 thereon.

25 The free end of the spring 28 serves to hold the movable plate 24 in position upon the plate 17, and to yieldingly resist all vertical movement with respect thereto.

30 The operation of the device is largely obvious. It is to be noted, however, that when the end of a cooperating or detachable contact element, as, for example, a cylindrical pin 32 is first introduced between the flaring ends 18, 25 of said plates 17, 24, respectively, only a slight inward pressure is necessary, as the movable plate 24 in pivoting against the free end of the spring 28 only slightly opposes or resists the insertion of the end of said contact pin 32. This resistance to the inward movement of the contact pin 32 gradually increases until the end thereof passes the point under the forward end of the spring 28 by which time the plates 17, 24 will be brought into parallelism, and into full engagement with the pin 32.

50 Further, it is to be noted that where the contact element 33 to be received intermediate the plates 17, 24 is flat or of tapering form, the same will be engaged upon its opposite sides adjacent to its longitudinal edges by the flat flanges 22, 26 at the opposite longitudinal edges of said plates 17, 24, as shown at Fig. 5, and a full electric connection thereby established between said parts.

55 It will, of course, be understood that my invention is not confined to use in connection with an attachment plug or the like, but that the same may be employed in all types of electric apparatus in which one set of contact members is carried by such apparatus and adapted to receive a cooperating contact element forming part of or connected to another cooperating device or apparatus.

Having thus described my said invention what I claim and desire to secure by Letters Patent is:

1. A device of the character described comprising a rigid plate having a longitudinal groove therein, guides extending upwardly from the opposite edges of said plate, a movable plate having a longitudinal groove therein registering with the groove in said rigid plate, projections on the opposite edges of said movable plate and working within said guides, and a spring secured at one end to said rigid plate and having its free end engaging said movable plate at a point about midway between the ends of said movable plate, substantially as specified.

15 2. A device of the character described comprising a rigid plate having a longitudinal groove therein, longitudinal flanges extending laterally from each side of said groove, a pair of guides extending upwardly from the opposite outer edges of said longitudinal flanges, a movable plate having a longitudinal groove therein registering with the groove in said rigid plate, longitudinal flanges extending laterally from the opposite edges of said groove, projections extending outwardly from the outer edges of said longitudinal flanges midway of the length of said movable plate and working within the guides on said rigid plate, and a spring secured at one end to one end of said rigid plates and having its other end extending forwardly and engaging said movable plate at a point about midway between the ends of said movable plate, substantially as specified.

20 3. A device of the character described comprising a rigid plate having a longitudinal groove therein, longitudinal flanges extending laterally from each side of said groove, a pair of guides extending upwardly from the opposite outer edges of said longitudinal flanges, a movable plate having a longitudinal groove therein registering with the groove in said rigid plate, longitudinal flanges extending laterally from the opposite edges of said groove, said rigid and said movable plates being adapted to receive therebetween removable contact members of different cross-sectional configurations, projections extending outwardly from the outer edges of said longitudinal flanges midway of the length of said movable plate and working within the guides on said rigid plate, and a spring secured at one end to one end of said rigid plate and having its other end extending forwardly and engaging said movable plate at a point about midway between its ends, substantially as specified.

25 4. A device of the character described comprising a rigid plate having a longitudinal groove therein, longitudinal flanges extending laterally from each side of said

- groove, a pair of guides extending upwardly from the opposite outer edges of said longitudinal flanges, a movable plate having a longitudinal groove therein registering with the groove in said rigid plate, longitudinal flanges extending laterally from the opposite edges of said groove, projections extending outwardly from the outer edges of said longitudinal flanges midway of the length of said plate and working within the guides on said rigid plate, a spring, and means for securing said contact device to a conductor; said means also serving to secure said spring to said rigid plate, substantially as specified.
5. A device of the character described comprising a rigid plate having a longitudinal groove therein, longitudinal flanges extending laterally from each side of said groove, a pair of guides extending upwardly from the opposite outer edges of said longitudinal flanges; said rigid plate terminating in a flat end having upwardly extending flanges at its opposite sides, a movable plate having a longitudinal groove therein and 25 longitudinal flanges extending laterally from the opposite edges of said groove, projections extending outwardly from the outer edges of said longitudinal flanges midway of the length of said plate and working 30 within the guides on said rigid plate, a spring having one end disposed upon the flat end of said rigid plate intermediate the upwardly extending flanges thereon, and its other end free and engaging said movable plate midway between its ends, and a screw 35 extending through said first-mentioned end of said spring and the flat end of said rigid plate for securing said parts together and to a conductor, substantially as specified. 40
- Signed at the city of New York, in the county and State of New York, this 29th day of July, one thousand nine hundred and twenty-one.

THOMAS D. FINIZIO.
